US00D929976S

(12) **United States Design Patent** (10) **Patent No.:** **US D929,976 S**
(45) **Date of Patent:** **** Sep. 7, 2021**

(54) **TERMINAL FOR NETWORKS**

(71) Applicant: **Samsung Electronics Co., Ltd.**, Suwon-si (KR)

(72) Inventors: **Jihee Kwak**, Suwon-si (KR); **Moonjung Jang**, Suwon-si (KR); **Eunae Lee**, Suwon-si (KR); **Soyoon Jeon**, Suwon-si (KR); **Jihyun Moon**, Suwon-si (KR)

(73) Assignee: **SAMSUNG ELECTRONICS CO., LTD.**, Gyeonggi-Do (KR)

(**) Term: **15 Years**

(21) Appl. No.: **29/712,084**

(22) Filed: **Nov. 5, 2019**

(30) **Foreign Application Priority Data**

Sep. 9, 2019 (KR) 30-2019-0043344

(51) **LOC (13) Cl.** **14-03**

(52) **U.S. Cl.**

USPC **D14/240**

(58) **Field of Classification Search**

(57) **CLAIM**

The ornamental design for a terminal for networks, as shown and described.

DESCRIPTION

FIG. 1 is a front perspective view of a first embodiment of a terminal for networks, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view of a second embodiment of a terminal for networks, showing our new design;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof; and,

FIG. 16 is a rear perspective view thereof.

The broken lines illustrating portions of the terminal for networks form no part of the claimed design.

1 Claim, 12 Drawing Sheets
